CLAIM

The ornamental design for a spherical disposable cup, as shown and described.

DESCRIPTION

FIG. 1 is a top perspective view of a spherical disposable cup, showing my new design;

FIG. 2 is a bottom perspective view thereof;

FIG. 3 is a front elevational view thereof, the rear elevational view being a mirror image thereof;

FIG. 4 is a top plan view thereof;

FIG. 5 is a bottom plan view thereof; and,

FIG. 6 is a cross-sectional view taken along line 6-6 in FIG. 4.

The dot-dash broken lines in FIG. 6 depict the bounds of the claimed design and form no part thereof.

1 Claim, 6 Drawing Sheets
